UNITED STATES PATENT OFFICE.

GEORGIA ALLEN POST, OF FOREST HILLS, NEW YORK.

DESIGN FOR A STATUETTE OR SIMILAR MINIATURE FIGURE.

Application filed June 5, 1923. Serial No. 6,390. Term of patent 14 years.

To all whom it may concern:

Be it known that I, GEORGIA ALLEN Post, a citizen of the United States, residing at Forest Hills, in the borough and county of Queens, city and State of New York, have invented a new, original, and ornamental Design for a Statuette or Similar Miniature Figure, of which the following is a specification, reference being had to the accompanying drawing, forming a part hereof.

Fig. 1 of the drawing is a front elevation of a statuette or similar miniature figure embodying my new design, and Fig. 2 is a side elevation thereof.

The particular features of my design comprise a horse-shoe employed for the legs of the figure, and a four-leaf clover used for a hat. A subsidiary feature consists in a wishbone suspended from a necklace worn around the neck of the figure.

I claim:

The ornamental design for a statuette or similar miniature figure as shown and described.

GEORGIA ALLEN POST.
